INTERNAL-COMBUSTION MOTOR

Application filed January 31, 1927. Serial No. 164,898.

This invention relates to an improvement in internal combustion motors and has for its primary object the purpose of providing an improvement in a two-cycle type of motor wherein the thermal efficiency of the motor is maintained at small fractions of full load. Another object of the invention is in providing the motor with improved means for feeding the gaseous fuel to the cylinders of the motor.

A further object of the invention is in providing means for controlling the admittance of gaseous fuel to the cylinders whereby the fuel may be admitted to one or more of the cylinders of a multiple cylinder motor.

A still further object of the invention is in providing an internal combustion motor with means whereby a volume of fuel under varying pressure is maintained ready for admittance to one or more cylinders of a multiple cylinder motor operating at variable speeds.

Another object of the invention is in providing the fuel pressure providing means with means for by-passing varying amounts of fuel attendant with the number of cylinders being operated or to which fuel is being admitted.

A further object of the invention is in providing means for controlling the admittance of gaseous fuel to the multiple cylinders of the motor and for cutting off the admittance of fuel to the cylinders for providing a braking means for the motor.

Other and further objects will appear in the specification and be specifically pointed out in the appended claims, reference being had to the accompanying drawings exemplifying the invention, and in which,

Figure 1 is a longitudinal horizontal section taken through this improved motor on line I—I of Fig. 2.

Figure 2 is a transverse vertical section taken approximately on the line II—II of Fig. 1.

Figure 3 is a transverse vertical section taken approximately on the line III—III of Fig. 1.

Figure 4 is a plan view partly in section of the operating mechanism of the inlet port controlling means.

Figure 5 is a side elevation of Fig. 4.

Figure 6 is a transverse vertical section taken approximately on the line VI—VI of Fig. 5.

Figure 7 is a developed diagrammatic illustration partly in section showing the manner of operation of the inlet port controlling means with respect to the cylinders of the motor and the by-passing means.

Referring by numerals to the accompanying drawings 9 designates a cylinder block in which eight vertically disposed alining cylinders are provided, said cylinders being numbered 1, 2, 3, 4, 5, 6, 7 and 8 respectively, the cylinder 1 being located at the front of the motor. Reciprocal within each cylinder is a piston 10 each having a wrist pin 11 and connected to each wrist pin is a connecting rod 12, said rods being cooperable with respective throw arms 13 of the crank shaft 14 which is disposed in the crank case 15, the cylinder block 9 being mounted on said crank-case.

Disposed on one side of the eight cylinders is an exhaust manifold 16 having a series of spaced openings 17, each opening being in alinement with a respective exhaust port 18, each of said exhaust ports leading from a respective cylinder and disposed on the other side of said cylinders is a horizontal intake manifold 19 having a series of spaced openings 20, each opening being in alinement with an intake port 21 of a respective cylinder.

The intake manifold 19 is provided at one end with a slotted aperture 22 said aperture connecting with the cross portion 23 of a tubular by-passing member 24 which extends the proximate length of the motor, said by-passing member 24 having a downwardly bent portion 25 which communicates with the lower end or suction end of a pump housing 26. Mounted in the pump housing 26 is a pump 27 which is comprised of a pair of meshing gears 28 and 29, the gear 28 being keyed to the crank shaft 14, and leading from the upper end of the pump housing 26 is a tubular extension 30 which communicates with an enlargement 31 which is formed adjacent the rear end of the intake manifold 19. In com-

munication with the by-passing member 24 is a carburetor 32 through which gaseous fuel is supplied to the by-passing member.

Turnably mounted in the intake manifold 19 is a tubular member 33 having eight outlet openings designated as 1^a, 2^a, 3^a, 4^a, 5^a, 6^a, 7^a, and 8^a, each opening being in cooperative alinement with a respective cylinder and formed in the tubular member 33 within the enlargement 31 of the intake manifold 19 are 10 a series of openings 34. The rear end 35 of the intake manifold 19 is threaded as designated at 36 and mounted on said threaded end is a gland nut 37 and secured in the rear end 15 of the tubular member 33 by a pin 38 and extending through the gland nut 37 is a short shaft 39.

Securely mounted on the extending end of the shaft 39 is a cam-wheel 40 having projections 41, 42, 43 and 44 respectively formed on its periphery, and rigidly secured on said shaft adjacent said cam-wheel is a bevel gear 45. In mesh with the bevel gear 45 is a segment 46, said segment being mounted on a 25 supporting shaft 47 and cooperably, connected to said segment is a push rod 48, said rod at its opposite end being connected to a bell crank foot lever 49. The foot lever 49 is 30 swingingly supported on the shaft 50 and for holding the foot lever in normal position a coil spring 51 is provided, said spring at one end bearing against a rigid projection 52 and at its opposite end against the securing yoke 53 of the push rod 48 and cooperable 35 with said rod 48 for pushing it is a finger 54 which is adapted to bear against the shoulder 55 which is formed or mounted on the rod 48, said finger being secured to the turnable rod 56.

40 The forward end of the tubular member 33 is provided with a by-passing outlet opening 57, one end of said opening having a straight edge 58 whereas the opposite edge of the opening is serrated as designated at 59, said 45 serrated edge having cutting-off portions A, B and C extending into the opening expance and are adapted to cooperate with the elongated aperture 22 of the intake manifold 19 when the member 33 is turned in the manner 50 hereinafter described.

55 From the disclosure of Fig. 7 in which the size of the tubular member having the eight outlet openings numbering from 1^a to 8^a inclusive is enlarged, it is to be noted that none of said outlet openings are in communication with the intake port 21 whereas in Fig. 1 the outlet opening 2^a of the tubular extension 33 is in alinement with the intake port 21 of No. 2 cylinder. Furthermore it is to be noted 60 from a further inspection of Figs. 1 and 7 that the outlet openings are of greater and lesser lengths in the periphery of the tubular member 33 in which the outlet opening 2^a is the longest and will be the first to communicate with intake port 21 of No. 2 cylinder

when the tubular member 33 is turned in the direction of the arrow 60 in Fig. 7 whereas the outlet opening 6^a is the next in length and will be the next opening to communicate with the port 21 of No. 6 cylinder and whereas the two outlet openings 4^a and 8^a are of the same length and will be the next in order to communicate with port 21 of respective cylinders No. 4 and No. 8; the remaining outlet openings 1^a, 3^a, 5^a and 7^a being of equal length 70 although of shorter length than all of the other said outlet openings and being the last openings of the tubular member 33 to communicate with port 21 of respective cylinders Nos. 1, 3, 5 and 7.

75 With the aforesaid detailed description of the outlet openings of the tubular member 33 in view, it is obvious therefore that a stepping procedure of opening the port 21 of respective cylinders is provided when the tubular member 33 is turned and while a means for turning the tubular member 33 is shown, other means than that shown may be used without departing from the spirit or intent of the invention. In this connection when it 80 is desired to put this improved motor into operation, the crank shaft 14 is turned by the usual starting mechanism (not shown) and at the same time gaseous fuel is permitted to pass from the carburetor 32 into the downwardly bent portion 25 of the by-passing member 24 and inasmuch as the pump gear 28 is keyed to the crank shaft 14, said gear will cause its mating gear 29 to revolve there- 85 with in the housing 26 thereby creating a suction action in the manner as is well known and in which the gaseous fuel and air will be drawn from the carburetor into the bent portion or discharge end 25 of the by-passing member 24 and in which the gaseous fuel 90 will be discharged into the extension 30 from the pump housing 26 and into the enlargement 31 of the intake manifold 19 from where the gaseous fuel will be admitted into the tubular member 33 through the openings 34 of said member 33. Simultaneous with the 95 turning of the crank shaft 14 by the starter, the operator when pressing on the foot lever 49 will move the push rod 48 and cause the segment 46 to turn the bevel gear 45 and in- 100asmuch as said gear is secured to the shaft or stub 39, the tubular member 33 will be turned in the direction of the arrow 60 in Fig. 7 and in which the cam-wheel 40 will be turned by reason of it being rigidly secured to the shaft 39. The turning of the cam-wheel 40 will permit the roller 61 to be actuated downwardly by the spring 62 against the incline face 63 of the cam-wheel 40, the action of the roller on said incline face tending to push 105 the cam-wheel and assist the turning thereof and in which the tubular member 33 will be moved with some rapidity, the action of said roller against the incline face 43 assist- 110 ing in a downward movement of the foot le- 115

ver 49 and when the roller 61 has reached the bottom of the incline face 63 in which a groove or recess 64 is provided, said roller will tend to hold the cam-wheel 40 and incidentally the tubular member 33 against further turning in a determined position with a given effort applied to the foot lever 49. This turning of the cam-wheel 40 to a position wherein the roller 61 has become seated in the groove 64 coincidently turned the tubular member 33 to the position wherein the opening 2^a is placed in communication with port 21 of No. 2 cylinder and inasmuch as gaseous fuel has been admitted into the member 33, fuel will pass through the opening 2^a and into its relateable cylinder through port 21 during the intermittent opening of said port by the piston 10 of No. 2 cylinder. Obviously the timed sparking of the spark plug (not shown) of No. 2 cylinder will explode the fuel which has been injected into the cylinder through the port 21 of said cylinder in timed relation with each compression stroke of the piston and the motor therefore is put in operation by the propelling thrusts of the piston on the crank shaft.

Before operating the tubular member 33 with respect to admitting fuel through outlet 2^a to No. 2 cylinder and from a further inspection of Fig. 7, it is to be noted that the by-passing outlet opening 57 is in communication with the elongated aperture 22 of the intake manifold 19, therefore when the crank shaft 14 is turned by the engine starting mechanism, the gaseous fuel pump 27 will simultaneously deliver during each revolution of crank a sufficient volume of fuel to re-fuel all cylinders of the motor but as no outlet openings 1^a to 8^a inclusive of the tubular member 33 register with the cylinder intake ports 21, no fuel can be delivered to any cylinder and therefore all gaseous fuel pumped by fuel pump 27 must find its way through opening 57 of member 33 and thereby be by-passed through the aperture 22 into by-passing member 24 which conducts the by-passed gas back to the fuel pump suction. As no gas has left the recirculating system provided by by-passing member 24, tubular member 33 and pump 27, obviously no fuel mixture will be drawn from the carburetor and the pressure of the circulating gas in the tubular member 33 will be that necessary to deliver the entire pump capacity through the aperture 22. When however the member 33 was turned for placing outlet opening 2^a in communication with port 21 of cylinder No. 2, the incline edge 65 of cutting-off portion A was simultaneously moved to a cutting-off position with respect to the aperture 22 in which said aperture was shortened in effective length thereby restricting the discharge of fuel through said aperture from member 33 to an extent equal to the amount of fuel

delivered for consumption in No. 2 cylinder of the motor. When the member 33 was turned, the approximate distance of peripheral travel of said member was that as designated at D between the dotted lines in Fig. 7 with respect to placing the outlet opening 2^a in communication with port 21 and as indicating the amount of cut-off of the projection A with respect to the aperture 22.

When the operator desires to provide the next cylinder in the order of operation with fuel for the purpose of providing the crank shaft 14 with more turning power, the foot lever 49 is further pressed downwardly and in which the segment 46 will be further operated by actuation of the push rod 48 thereagainst and the bevel gear 45 will be further turned thereby operating shaft 39 and further turning the cam-wheel 40 and the roller 61 will be forced to ride from its holding position in the groove 64 up the incline face 66 and over the projection 41, down the incline face 67 and into the groove 68 and in which the spring 62 will become effective on the roller 61 as it travels down the incline face 67, the spring pressure on the roller tending to quickly force the cam-wheel in its turning movement thereby assisting the downward pressure of the operator on the foot lever 49 and in which the roller 61 upon seating in the groove 68 will tend to hold the cam-wheel 40 and incidentally the tubular member 33 against further turning providing the foot pressure of the operator on the lever 49 is not increased. This further turning of the member 33 during the time when the roller 61 was traveled upon the face 66 of the cam-wheel 40, caused the cutting-off portion A to move the approximate distance as designated at E between the dotted lines in Fig. 7 and further cut off or narrow the length of the aperture 22 thereby causing a still greater pressure to be maintained in the member 33 and consequently a greater discharge of fuel will be injected in cylinder No. 2 through outlet 2^a of member 33 thereby increasing the intensity of the intermittent firing of said cylinder. As roller 61 traveled down the face 67 towards the groove 68 the peripheral travel of the member 33 was the approximate distance as indicated at F between the dotted lines in Fig. 7, this distance of peripheral travel placing outlet opening 6^a of member 33 in communication with port 21 of No. 6 cylinder and simultaneously placing the cut away part 69 of the opening 57 in communication with the aperture 22 thereby lengthening the expanse of the aperture so that a larger by-passing outlet is permitted from the member 33 than was permitted when that part of portion A indicated at E was in cutting-off relation with the aperture 22. This enlarging area of the aperture 22 is to be noted occurs at the time when No. 6 cyl-

inder is permitted to operate along with No. 2 cylinder for the reason that two cylinders operating at the same time with respect to the pistons thereof, will provide more turning effort to the crank shaft 14. The purpose therefore of having cutting-off portion A to co-operate with the aperture 22 is to restrict the amount of fuel by-passed so that a greater pressure can be built up in the member 33 so that the first (No. 2) operating cylinder will receive a relative greater amount of fuel charge just prior to the second (No. 6) cylinder being operated so that the turning effort at the crank shaft will be a gradual increase.

Upon the operator providing further pressure to the foot lever 49, the roller 61 is forced upwardly on the incline face 70 when the cam-wheel 40 is further turned and during the travel of the roller upon said face to the top of the projection 42, the member 33 is further turned and in which the peripheral travel thereof will be that as indicated at G between the dotted line in Fig. 7 in which the incline edge 71 of the cutting-off portion B will be moved to a cutting-off position with respect to the aperture 22 in which the length of said aperture will be further narrowed and causing a greater pressure to be built up in the member 33 and consequently the cylinders Nos. 2 and 6 will be given greater or supercharges of fuel and more power or turning effort will be given to the crank shaft 14 from the greater propelling thrusts of the pistons of said cylinders. With a further slight increase of pressure on the foot lever 49 the roller 61 is caused to travel down the incline face 72 to the groove 73 of the cam wheel 40, and the member 33 is further turned with rapidity due to the combined force at foot lever 49 and of spring 62 forcing roller 61 against incline face 72 and in which the approximate distance of peripheral travel of said member as indicated at H between the dotted lines in Fig. 7, will place outlet openings 4^a and 8^a in communication with port 21 of respective cylinders Nos. 4 and 8 and in which the cut-away portion 74 of the opening 57 of the member 33 will be presented to the aperture 22 thereby again lengthening the aperture so that a greater discharge can be made through said aperture into the by-passing member 24 than was given to said by-passing member when the cutting-off portion B was presented to the aperture 22 for the reason that cylinders numbering 2, 4, 6 and 8 are in operation with respect to the pistons thereof giving minimum propelling thrusts to the crank shaft and consequently the crank shaft may revolve at a greater speed and the pump 27 will then maintain a greater pressure in the member 33 and consequently the requirement of the enlargement of the discharge aperture 22 for

the purpose of by-passing approximately one-half of the fuel from the member 33.

Further downward pressure on the foot lever 49 will cause the roller 61 to travel upwardly on the incline face 75 of the cam-wheel 40 from holding engagement with the groove 73, as said cam-wheel is turned the length of said face to the top of the projection 43 corresponding to the peripheral distance indicated at I between the dotted lines in Fig. 7 in which the inclined edge 76 of the cutting-off portion C of the member 33 will be moved in cutting-off position with the aperture 22 as said member 33 is further turned, and the pressure in the member 33 will be again further increased thereby supercharging the cylinders 2, 4, 6 and 8 so that the pistons thereof will be operated with greater impulses and as the roller 61 is traveled down the incline face 77 to the groove 78, the outlets 1^a, 3^a, 5^a and 7^a are quickly moved to positions in communication with the ports 21 of respective cylinders Nos. 1, 3, 5 and 7 and simultaneous therewith the cut-away portion 79 of the outlet opening 57 is moved in operative position with the aperture 22 of the by-passing member 24 as the periphery of the member 33 is traveled an approximate distance as indicated at J between the dotted lines in Fig. 7. Further movement of the member 33 by actuating the foot lever 49 downwardly to a position wherein the roller 61 will be forced up the incline face 78 and over the projection 44 and against the stop 81 on the cam-wheel 40, will cause the incline edge 80 of the opening 57 of the member 33 to progressively close or cut-off the aperture 22 so that there will be no by-passing of the fuel from the member 33 to the by-passing member 24 and a variable pressure will therefore develop in the member 33 for supplying fuel to all of the cylinders for the reason that the peripheral portion indicated at K between the dotted lines in Fig. 7 will remain in alignment with the ports 21 of all of the cylinders.

From the aforesaid description of putting the motor into operation in which one cylinder is first put in operation and subsequently other cylinders until all of the cylinders of the motor are operating thereby gradually increasing the turning effect on the crank shaft 14, it is obvious therefore that a variable torque of equally spaced impulses is provided to the crank shaft in which a smooth flow of power is capable of being transmitted from the crank shaft to the load.

After the operator has placed all of the cylinders of the motor into operation and it is desired to continue operating all of the cylinders, the operator will maintain foot pressure on the foot lever 49 against the pressure of the spring 51 which bears against the projection 52 and against the yoke 53, this maintained position of the foot lever 49 retaining the cam-wheel 40 in its farthest

5 moved position with respect to all of the outlet openings 1^a to 8^a inclusive being in communication with respective ports 21 of respective cylinders, but when the operator desires to shut down the motor, the release of foot pressure on foot lever 49 will permit the spring 51 to become active on the yoke 53 of push rod 48 and push said rod rearwardly thereby causing the segment 46 to retroact on the bevel gear 45 and in which said gear will retroact on the member 33 and turn said member to its normal position, the return of said member to its normal position moving the outlet openings 1^a to 8^a inclusive out 10 of communication with the ports 21 of respective cylinders thereby preventing further recharge of the cylinders with gaseous fuel from the member 33 and in which the motor will become inoperative.

15 20 In the use of a motor of this improved character as a power plant to a vehicle such as an automobile and assuming that all of the eight cylinders of the motor are in operation and the automobile is being driven by the motor on a comparatively level stretch of roadway and the operator of the automobile believes that the power derived from the eight operating cylinders is not required to propel the automobile over the level stretch 25 30 of roadway, the operator upon releasing the pressure somewhat from the lever 49 will permit the spring 51 to force the push rod 48 rearwardly thereby causing the segment 46 to retroact on the gear 45 in which the member 33 will be turned rearward and the outlet 35 40 openings 1^a, 3^a, 5^a and 7^a of the member 33 will be moved to positions out of communication with respective ports 21 of respective cylinders 1, 3, 5, and 7, the operator at this position of operation of the member 33 holding the foot lever 49 against further upward movement and in this position of the member 33 the roller 61 will be positioned in the groove 73 of the cam-wheel 40, said roller 45 tending to hold the cam-wheel and incidentally the member 33 in the position desired by the operator. This set position of the member 33 therefore permits only the outlet openings 2^a, 4^a, 6^a and 8^a to be in position of communication with respective ports 21 of respective cylinders 2, 4, 6 and 8 in which only four cylinders will be providing the crank shaft 14 with turning power for propelling the automobile and the idle cylinders 1, 3, 5 and 55 60 65 7 will serve as cooling agents to the operating cylinders inasmuch as no explosions are occurring in cylinders 1, 3, 5 and 7. If the operator of an automobile having this improved motor as a power plant therefor desires to idle the motor when the automobile is at the curb, the member 33 upon being operated to the position wherein only outlet opening 2^a thereof is in communication with port 21 of No. 2 cylinder, will therefore permit only one cylinder to be operated for pro-

viding turning effort to the crank shaft 14 thereby economizing on the amount of gaseous fuel used in which approximately $\frac{1}{8}$ of the fuel pumped into member 33 will be bypassed through aperture 22 into by-passing member 24 and recirculated by the pump 27 whereas approximately $\frac{1}{8}$ of the fuel forced into member 33 by the pump will be injected through port 21 of No. 2 cylinder. Obviously two cylinders can be placed into operation 70 75 for idling the motor if so desired by manipulating the member 33 to the position wherein outlet opening 6^a is positioned so as to permit fuel to be forced into No. 6 cylinder through port 21 thereof as outlet opening 6^a is the next outlet opening to be placed in communication with its respective cylinder after outlet opening 2^a has been placed in communication with its respective cylinder.

80 85 In operating an automobile powered by this improved motor in traffic and the automobile is stopped awaiting the traffic signal to "go", the member 33 can be operated to the position for turning the crank with either one or two cylinders and as soon as the signal is given to "go", the operator upon pressing the foot lever all the way down will operate the member 33 to the positions placing all of the outlet openings to the remaining cylinders in positions of operation so as to make 90 a quick get away thereby during the following revolution of crank and permitting refueling of all the engine cylinders thus applying the full turning effort of all pistons on the crank shaft 14 to the propelling parts 95 of the automobile as the piston of respective cylinders uncover respective inlet ports.

100 105 When less than all cylinders are firing, a varying proportion of pumped by-passed gas is recirculated through by-passing member 24 and mixed with increasing carbureted gas, this condition making for a thorough volatilized gas mixture.

110 115 When an automobile equipped with this improved motor is descending a relatively long hill, by operating the member 33 to a closed position with respect to the ports 21 of the cylinders of the motor and by leaving the motor in gear with the driving shaft of the vehicle, the turning or driving of the 120 dead motor by the driving shaft being driven by the traction wheels of the automobile, the motor will provide an ideal brake for the automobile by the pump 27 working against the pressure contained in the member 33 and forcing the compressed gaseous fuel through the aperture 22.

125 130 When it is desired to operate the member 33 by hand instead of manipulating the foot lever 49 the rod 56 which may be extended adjacent to the operator of the automobile and upon being turned in the direction of the arrow 82 will cause the finger 54 to bear against the shoulder 55 and force the push rod 48 forwardly thereby operating the seg-

ment 46 and turning the gear 45 which is mounted on the shaft 39, the roller 61 co-operating with the incline faces of the cam-wheel 40 in the same manner as when the cam-wheel was operated by movement of the 5 foot lever 49. By releasing the turning pressure on the rod 56 the spring 51 will move the push rod 48 rearwardly and in which the member 33 will be returned to its 10 cutting-off position. The rod 56 may be made cooperative with certain retaining means for holding the member 33 in the desired position with respect to certain of the outlet openings thereof communicating with 15 respective cylinders.

From the foregoing, attention is called to the varying of power output of motor by varying in direct ratio, the number of operative cylinders thus making possible the employment of the respective number of cylinders at an approximate full loading per cylinder under which condition compression of fuel charge at even small fractions of maximum motor power will be obtained from 20 power impulses acquired from the firing of fuel charges at the maximum designed compression pressures which results in maximum possible fuel economy.

The showing of cut-off portions A, B and 30 C operating on the length of by-passing slot 22 is intended to function with the selected operative number of cylinders under manual control only but the projecting portions may be omitted thereby restricting the aperture 35 22 in direct ratio to operative number of cylinders under which condition an auxiliary resistance per unit of cylinder area of aperture 22 must be provided to automatically further decrease the relative by-pass 40 aperture area per cylinder of the slot 22 with increase of engine speed.

For providing a more thorough scavenging of the burnt gases of the cylinders of this improved motor, an upwardly extending 45 projection 83 having a deflecting face 84 is formed on top of each piston 10 said deflecting face adapted to receive the injected gaseous fuel through respective ports 21 which are disposed tangentially to each respective cylinder and direct the gases upwardly in each 50 cylinder in the manner as shown by the arrows in the cylinder in Fig. 2 and by reason of the gases being received into the cylinder tangentially thereto, the wall of each cylinder 55 will cause the gases to swirl around the cylinder as they travel upwardly as shown by the arrows in No. 2 cylinder of Fig. 1, said upward swirling rushes of gases in each cylinder forcing the burnt gases in each cylinder downwardly into respective outlet ports 60 18 and into the exhaust manifold 16.

This improved multiple cylinder two cycle motor when operating at less than full load, a consequently fewer number of total cylinders firing at full load of motor results in

the radiation of the idling cylinders which are cast en bloc with those firing, thus making possible a faster cooling of an overheated motor by permitting the motor to turn over with either one or two cylinders firing, then 70 by killing or stopping the motor.

For preventing possible back-fire from the cylinders into respective inlet ports 21, a wire gauze portion 83^a is mounted between each port 21 and the intake manifold 19.

What I claim is:

1. An internal combustion motor having a plurality of cylinders, an intake manifold, a port leading from said manifold to each respective cylinder, and controlling means co-operable with all of said ports independent of normal cyclic operation located in said manifold adapted to be operated to open one or more of said ports. 80

2. An internal combustion motor having a plurality of cylinders, an intake manifold, a port leading from said manifold to each respective cylinder, controlling means located in said manifold adapted to open one or more of said ports, and means for actuating said controlling means adapted to be progressively moved. 90

3. An internal combustion motor having a plurality of cylinders, an inlet port leading to each of said cylinders, controlling means for all of said ports, said controlling means adapted to be actuated so as to permit fuel to be continually admitted to one of said ports and when further actuated adapted to permit fuel to be continually admitted 100 to another one of said ports. 95

4. An internal combustion motor having a plurality of cylinders, an inlet port leading to each of said cylinders, controlling means for said ports, said controlling means adapted to be progressively actuated so as to first admit fuel to one of said ports, then to another of said ports, then to simultaneously admit fuel to a pair of said other ports and finally to simultaneously admit fuel to all 110 of the other said ports. 105

5. An internal combustion motor having a plurality of cylinders, an intake manifold, a port leading from said manifold to each respective cylinder, and controlling means located in said manifold adapted to be progressively actuated to open one or more of said ports as required and to close all of said ports. 115

6. An internal combustion motor having a plurality of cylinders, an inlet port leading to each of said cylinders, controlling means independent of normal cyclic operation co-operable with all of said ports, said controlling means adapted to be actuated so as to admit fuel to one of said cylinders and when further actuated adapted to admit fuel to other of said cylinders. 120

7. An internal combustion motor having a plurality of cylinders, an inlet port leading to each of said cylinders, controlling means 130

- independent of normal cyclic operation co-operable with all of said ports, said controlling means adapted to be actuated so as to admit fuel to one or more of said cylinders.
5. An internal combustion motor having a plurality of cylinders, an intake manifold, a port leading from said manifold to each respective cylinder, and controlling means co-operable with all of said ports located in said manifold adapted to open one or more of said ports as required, and means for actuating said controlling means.
10. An internal combustion motor having a plurality of cylinders, an intake manifold, a port leading from said manifold to each respective cylinder, controlling means located in said manifold adapted to be manually set to open or close certain of said ports, and means for maintaining a pressure in said manifold.
15. An internal combustion motor having a plurality of cylinders, an intake manifold, a port leading from said manifold to each respective cylinder, controlling means located in said manifold adapted to be set to open or close certain or all of said ports, a pump for maintaining a pressure in said manifold, and by-passing means from said manifold to said pump.
20. The herein described method of charging the cylinders of a multiple cylinder motor consisting of selectively admitting gaseous fuel to one or more of the cylinders, then to admit fuel to other of the cylinders, and to finally admit fuel to the remaining cylinders of the motor.
25. The herein described method of charging the cylinders of a multiple cylinder motor consisting of selectively admitting gaseous fuel to one or more of the cylinders.
30. The herein described method of charging the cylinders of a multiple cylinder motor consisting of selectively admitting normally operating gaseous fuel charges to one or more of the cylinders, then to admit fuel to other of the cylinders, and to finally admit fuel to the remaining cylinders of the motor.
35. An internal combustion motor having a plurality of cylinders, an intake manifold, a port leading from said manifold to each cylinder, and governing means located in the manifold being co-operable with all of said ports for opening or closing their communication with the manifold as required.
40. An internal combustion motor having a plurality of cylinders, an intake manifold, a port leading from said manifold to each cylinder, and governing means located in the manifold being co-operable with all of said ports for varying the torque output of the motor, said governing means being adapted to be set for opening or closing communication with the manifold.
45. An internal combustion motor having a plurality of cylinders, an intake manifold, a port leading from said manifold to each cylinder, and governing means located in the manifold being co-operable with all of said ports for varying the torque output of the motor by inducing quantity governing, said governing means being adapted to be set for opening or closing communication with the manifold.
50. An internal combustion motor having a plurality of cylinders, an intake manifold, a port leading from said manifold to each cylinder, controlling means for said ports, by-passing means co-operable with said controlling means, and graduating cut-off means under the control of said controlling means co-operable with said by-passing means.
55. An internal combustion motor having a plurality of cylinders, an intake manifold, a port leading from said manifold to each cylinder, controlling means for said port, by-passing means, and graduating cut-off means associated with the controlling means, said cut-off means being co-operable with said by-passing means for controlling the quantity of fuel by-pass.
60. An internal combustion motor having a plurality of cylinders, an intake manifold, a port leading from said manifold to each cylinder, controlling means located in said manifold co-operable with said ports, a pump for maintaining a pressure in said manifold, by-passing means from said manifold to said pump, and graduating cut-off means associated with the controlling means and co-operable with the by-passing means for controlling the quantity of fuel by-passed.
65. An internal combustion motor having a plurality of cylinders, an inlet port leading to each of said cylinders, controlling means for said ports, said controlling means when actuated in one direction adapted to admit fuel to one of said ports, and when further actuated adapted to admit fuel to other of said ports; said controlling means when actuated in another direction adapted to close communication of the fuel with said ports.
70. An internal combustion motor having a plurality of cylinders, an inlet port leading to each of said cylinders, controlling means for said ports, said controlling means adapted to be progressively actuated so as to admit fuel to certain of said ports in progressive order, and means for applying a retrograde movement to said controlling means for closing communication of the fuel with said ports.
75. An internal combustion motor having a plurality of cylinders, an inlet port leading to each of said cylinders, controlling means co-operable with said ports for permitting fuel to enter said ports, said controlling means also being adapted to be positioned

to prevent fuel being admitted to any of said ports.

23. An internal combustion motor having a plurality of cylinders, an intake manifold, 5 a port leading from said manifold to each cylinder, controlling means located in said manifold cooperable with said ports, a pump for maintaining a pressure in said manifold, said controlling means adapted to be positioned to admit fuel from the manifold to either one or more of said ports, by-passing means from said manifold to said pump, and graduating cut-off means associated with the controlling means and cooperable with the 10 by-passing means for controlling the quantity of fuel by-passed.

24. An internal combustion motor having a plurality of cylinders, an intake manifold, a port leading from said manifold to each 20 respective cylinder, and controlling means independent of normal cyclic operation cooperable with said ports adapted to permit fuel to enter one or more of said ports.

25. An internal combustion motor having 25 a plurality of cylinders, an intake manifold, a port leading from said manifold to each respective cylinder, controlling means independent of normal cyclic operation cooperable with said ports adapted to permit fuel 30 to enter one or more of said ports, and means for maintaining a pressure on the fuel in said manifold.

26. An internal combustion motor having a plurality of cylinders, a port leading to 35 each cylinder, and controlling means cooperable with said ports adapted to be progressively actuated to open one or more of said ports as required and to close all of said ports.

40 27. An internal combustion motor having a plurality of cylinders, a port leading to each cylinder, and controlling means adapted to be progressively actuated to permit fuel to enter one or more of said ports as required.

28. An internal combustion motor having a plurality of cylinders, a port leading to each cylinder, and controlling means adapted to be progressively actuated to permit 50 fuel to enter one or more of said ports as required and to prevent fuel being admitted to any of said ports.

29. An internal combustion motor having a pair of cylinders and each cylinder having 55 an inlet port, means for controlling the admittance of fuel to said ports, said controlling means adapted to be actuated to permit fuel entering only one of said ports during when the motor is in operation.

60 30. An internal combustion motor having a pair of cylinders and each cylinder having an inlet port, means for controlling the admittance of fuel to said ports, said controlling means adapted to be actuated to permit 65 fuel entering only one of said ports during

when the motor is in operation, said controlling means also being adapted to be actuated to permit fuel entering both of said ports.

31. An internal combustion motor having 70 a pair of cylinders and each cylinder having an inlet port, means for controlling the admittance of fuel to said ports, said controlling means adapted to be actuated to permit fuel entering only one of said ports during 75 when the motor is in operation, said controlling means also being adapted to be actuated to permit fuel entering both of said ports and when further actuated to prevent fuel entering either of said ports.
